(74) Attorney, Agent, or Firm — Legends Law Group,
PLLC; Stephen H. Bean, Esq.(57) **CLAIM**

I claim the ornamental design for a blanket with pocket, as shown and described.

DESCRIPTION

FIG. 1 is perspective view of the blanket with pocket showing my new design;

FIG. 2 is a front view thereof;

FIG. 3 is a back view thereof;

FIG. 4 is a side elevational view thereof;

FIG. 5 is the opposite side elevation view thereof;

FIG. 6 is a top plan view thereof; and,

FIG. 7 is a bottom plan view thereof.

The broken lines in FIGS. 1-3 represent stitching lines.
